CLAIM

The ornamental design for a scrubber as shown and described.

DESCRIPTION

FIG. 1 is a top front left perspective view of a scrubber in accordance with the present invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a right rear perspective view thereof;

FIG. 9 is a left rear perspective view thereof;

FIG. 10 is a top rear perspective view thereof; and,

FIG. 11 is a top left perspective view thereof.

The broken lines in the drawing depict portions of the scrubber that form no part of the claimed design.

1 Claim, 11 Drawing Sheets
